METHOD FOR HYDROCARBON CONVERSION

Louis P. Evans, Woodbury, N. J., assignor to Socony-Vacuum Oil Company, Incorporated, a corporation of New York

Application September 27, 1947, Serial No. 776,471

4 Claims. (Cl. 196—52)

1

This invention pertains to a process for conversion of high boiling hydrocarbons in the presence of a particle-form contact mass material. This invention deals particularly with a process and apparatus for conversion of high boiling hydrocarbon fractions which contain varying amounts of asphaltic constituents.

Such conversion processes may involve treating, reforming, polymerization, oxidation, desulphurization, cracking, etc., of the hydrocarbons to form any of a number of products. A particularly important process is the catalytic cracking conversion of hydrocarbons, it being well known, for example that hydrocarbon fractions boiling above the gasoline boiling range may be converted to lower boiling gasoline containing hydrocarbons upon being subjected to contact with a suitable solid porous catalyst at temperatures of the order of 800° F. and upwards and at pressures usually above atmospheric.

Heretofore such conversion processes have been limited to the conversion of relatively light, clean, substantially tar or asphalt free petroleum feed stocks because of the tendency of the asphalt containing stocks to cause the formation of excessive deposits of coky contaminants on the catalyst which deposits cannot be economically removed. In order to avoid these heavy coke deposits which render the cracking process unfeasible, it has been the wide refinery practice to subject some high boiling petroleum feed stocks (when available with a broad boiling range) to a preliminary tar separation step, separate an easily vaporizable fraction from a liquid fraction which bears the asphaltic constituents and to subject only the vaporizable fraction to catalytic cracking while discarding the liquid tar separator bottoms. Since this discarded fraction may be made up of a large proportion of valuable oily constituents and a smaller proportion of asphaltic constituents, it is obvious that a large quantity of otherwise acceptable catalytic cracking feed stock is lost and unavailable as such in the prior art tar separator operation. When the crude residuum is not of such boiling range and does not contain substantial amounts of vaporizable gas oil, it has been considered in practice as being unsuitable as such for a cracking charge stock. The problem is becoming increasingly serious due to the fact that relatively low boiling petroleum crudes are becoming less plentiful and the crudes which are most readily available are high boiling crudes in which the oily constituents boil so high as to prevent their separation from asphaltic constituents by distillation processes

2

without subjecting them to temperatures at which undesirable thermal cracking and excessive coking occur. As a result in order to use such high boiling stocks at all, it is necessary first to subject them to a preliminary thermal coking step to provide some lower boiling oily fractions for a subsequent catalytic cracking operation. By-products from the coking process are a heavy liquid cut which may contain a substantial amount of oily constituents as well as asphaltic constituents and a very large amount of petroleum coke, the disposal of which often creates a serious refinery problem.

A major object of this invention is the provision of a process for conversion of high boiling asphalt bearing hydrocarbon fractions which process avoids the above described difficulties of the prior art.

Another object is the provision of a practical method and apparatus for hydrocarbon conversion which permits the catalytic conversion, without excessive coke formation, of the high boiling oily constituents present in high boiling petroleum residuums.

Another object is the provision of a process for catalytic conversion of hydrocarbons which is capable, without excessive coke formation of handling charging stocks boiling over a wide range of temperatures including very heavy constituents heretofore rejected as tar separator bottoms.

Another object of this invention is the provision of a new method and apparatus for the catalytic conversion of the oily constituents of high boiling liquid charging stocks which cannot be vaporized without cracking or coking.

These and other objects of this invention will become apparent from the following discussion.

The process of this invention in its preferred form is one wherein the asphalt bearing feed stock is contacted under suitable sorption conditions with a particle-form, porous inorganic oxide gel contact material which is characterized by a pore structure in which the percentage macropores is relatively low and the percentage of smaller pores is large and which preferably consists substantially of particles of 30 mesh size and larger size. By this contacting the oily constituents of the feed stock are sorbed in the pores of the contact material and the asphaltic constituents remain unsorbed. The unsorbed asphaltic constituents are separated from the contact material bearing sorbed oily constituents and the contact material is then passed through a conversion zone in admixture with a sufficient amount of hot regenerated contact material of

the same type to heat it to a temperature suitable for the conversion of the sorbed oily constituents to lower boiling hydrocarbon products. The gaseous hydrocarbon products are separated from the spent contact material which may be then subjected to regeneration.

It has long been known that when porous adsorbents such as bauxites and natural and treated clays are contacted with liquid petroleum fractions, the asphaltic constituents may be adsorbed on the clay and thus removed from the oily constituents. Such a process is commercially employed for the decolorizing of mineral oils by percolation of the oils through clay type adsorbents. The present process is the opposite of the so-called percolation and contact filtration processes for oil refining in that, by the present process, it is the oily constituent and not the asphaltic constituent which is sorbed by the contact material. This fundamental difference makes possible the combination cracking process of this invention and permits the elimination of the asphalt materials without contamination of the catalyst thereby. It has been found that porous contact materials, having a structure corresponding to that of an inorganic oxide gel having a substantially uniform porosity of low macropore

portant variables are time of contact between the liquid asphalt bearing charge and the sorbent in the sorption zone, temperature in the sorption zone, viscosity of the liquid charge, and to a lesser extent the ratio of liquid oil to sorbent charged to the sorption zone. Increasing time of contact and increasing temperature result in a decrease in the efficiency of separation of asphaltic and oily constituents. Decreasing viscosity of the liquid charge has the same effect. On the other hand increasing temperature and decreasing viscosity both result in more rapid sorption of the liquid oily constituents by the sorbent. If the ratio of sorbent to liquid charge is excessive some loss in separation efficiency results. By proper control of these variables some latitude in the average diameter of the sorbent employed may be provided. However, when the diameter of the particles becomes too small, the sorbent preferentially adsorbs the asphaltic constituents from the liquid charge in the same manner as well known oil filtering clays. This is shown in Table I below in which is tabulated the deasphalting results obtained on Mid-Continent residues using a silica-alumina gel type sorbent having a bulk density in the 4-8 mesh size range of about 0.7.

volume with an average pore diameter not exceeding about 125 Angstrom units and a particle size preferably not smaller than about 30 mesh for most operations, have the ability to sorb the oily constituents of a liquid hydrocarbon fraction while leaving substantially unsorbed the asphaltic constituents. Natural and treated clays and bauxites do not appear to have this property. The macropore volume of the contact material employed in the present invention should be relatively low so that the pore volume is mostly that of micropores. In general, the volume of macropores, that is, those pores having radii larger than 100 Angstrom units, should constitute less than about 30 percent of the total pore volume and preferably 10 percent or less. The measurement of pore size and pore size distribution in various porous materials is discussed in detail by L. C. Drake and H. L. Ritter in Industrial and Engineering Chemistry, analytical edition, volume 17, pages 782-791, 1945. The methods described there were essentially those employed in determining the bulk densities, average pore diameters, and other pore measurements of the absorbents employed in the present invention.

The size of the sorbent particles employed in the process of this invention is to some extent dependent upon the variables involved in any particular application of the process. These im-

50 It will be apparent from the above Table I that when the gel type sorbent particles were greater than 30 mesh size that even at relatively high temperatures and long contact periods the oily constituents of low viscosity and carbon residue was sorbed in the pores of the sorbent while the asphaltic constituents could be washed away with a suitable washing solvent, in this case benzol. On the other hand, in the case of sorbent 55 particles ranging from 30-60 mesh size, when the contact period was 24 hours (Experiment 4) or even 2 hours (Experiment 7), the sorbent acted similar to a normal filtering clay and preferentially adsorbed the asphaltic constituents. But when the contact time was reduced to two minutes (Experiment 5), the 30-60 mesh sorbent exhibited a preference for the oily constituents over the asphaltic constituents. When the particle size was reduced below 60 mesh, the sorbent preferentially adsorbed the asphaltic constituents even at very low contact periods (Experiment 6).

70 The effect of contact time and temperature is shown in Table II below in which the deasphalting results on an East Texas residuum having an original Saybolt Universal viscosity of 512 seconds at 210° F. and a Ramsbottom carbon residue of 11.1. In this experiment a silica-alumina gel type sorbent of 4-8 mesh size and 0.48 bulk density was employed.

In general it may be said that the particle size of the sorbent material particularly in the case of inorganic oxide gel type sorbents should be greater than about 60 mesh Tyler and preferably within the range about 0.022 to 1.0 inch average diameter. The best results may be obtained by limiting the sorbents within the range 0.03 to 0.20 inch average diameter and of reasonably uniform size. It is pointed out, however, that by proper control of the variables discussed hereinabove and also of the average pore diameter of the sorbent, operation according to the method of this invention may be obtained on sorbent particles outside the size ranges given although the results will be less satisfactory. It is contemplated that in its broader aspects this invention covers these latter operations as well as the operations within the specified preferred limits.

The porosity of the gel particles employed in the process of this invention is of fundamental importance. The degree of porosity is generally reflected in the bulk density of the gel composite used; the lower the bulk density, the greater being the degree of porosity. For the purposes of the present process, particles having bulk densities of between about 0.4 and 1.1 gram per cubic centimeter are preferred. The bulk densities indicated correspond to an average pore diameter of between about 20 and about 125 Angstrom units. Preferably, the sorbent used will have a bulk density between about 0.6 and about 0.8 gram per cubic centimeter. Gel particles having a bulk density greater than about 0.8 have been found to have excellent selectivity but poor sorbing capacity, while particles with a bulk density less than about 0.6 have relatively poor selectivity. However, since the selectivity of the deasphalting process improves with a decrease in temperature, particles with a bulk density less than 0.6 would be satisfactory for deasphalting stocks which can be processed at low temperatures.

The degree of porosity of a synthetic inorganic oxide gel will, in general, depend on the conditions under which it is prepared and allowed to set to gelation. A particularly convenient method of preparing gel particles used in the process of this invention is described in U. S. 2,384,946, issued September 18, 1945, to Milton M. Marisic. It is there disclosed that spheroidal particles of inorganic oxide gel may be prepared by mixing an acidic stream with a stream of sodium silicate and allowing the resulting sol to be ejected from a nozzle into an oil column, where the gel sets in the form of bead-like spheroids. The resulting gel spheres, after washing, drying and tempering, were of a size varying between about 4 and about 20 mesh. The gel beads so produced had a bulk density of between about 0.4 and about 1.1 and an average pore diameter of between about 20 and about 125 Angstrom units. They proved to be excellent selective sorbents for use in the process of this invention.

Likewise, irregularly shaped porous sorbent fragments or particles having the structure of

6

inorganic oxide gels may be used. However, in general, spheroidal particles are to be preferred, since attrition losses are then at a minimum and contamination with gel fines of the asphalt-bearing stock is substantially eliminated.

In general, siliceous gel particles will be used in the process of this invention, such as silica gel, silica-alumina gel, silica-zirconia gel, silica-thoria gel and the like. Porous sorptive silica glasses having a structure approaching that of a siliceous gel likewise are contemplated for use in the process described herein, it being necessary, however, that the porous glass employed have an average pore diameter less than about 125 Angstrom units, and a macropore volume of less than about 30 per cent of the total pore volume. The size of the porous glass particles must also be carefully controlled so as to obtain preferential sorption of the oily constituents. Usually particles of less than 60 mesh size are undesirable. It is also contemplated that within the scope of this invention other porous materials not of the inorganic oxide gel composition which have structures approaching that of a siliceous gel and are within the above specified pore size and particle size limits may be employed within the scope of this invention.

Typical of the porous glasses used are those described in U. S. 2,106,744, issued February 1, 1938, to Hood et al. There it is disclosed that a silica-alkali-boric oxide glass of suitable composition is prepared by a fusion process. Heat treatment of this glass results in separation of the glass into two phases; one phase is rich in alkali-boric oxide and is soluble in acids, while the other phase, which is insoluble in acid, consists of silica with a small amount of boric oxide. Extraction of this heat treated glass with acid results in a porous silica glass which can be employed as a porous absorbent separating medium in accordance with the present invention. Other types of sorbents which possess the physical structure and/or the sorptive characteristics of inorganic oxide gels may be employed within the scope of this invention.

The invention may be most readily understood by reference to the drawings attached hereto of which:

Figure 1 is a schematic arrangement of the system of this invention in which some of the apparatus is shown partially in section;

Figure 2 is a similar view of a modified arrangement; and,

Figure 3 is a diagrammatic flow sketch of still another modified arrangement.

All of these drawings are highly diagrammatic in form.

Turning now to Figure 1, for a study of the system of the present invention, an asphaltic bearing petroleum feed stock of relatively broad boiling range containing a vaporizable gas oil fraction as well as heavier oily and asphaltic constituents may be introduced through conduit 10 to tubes in a furnace 11 wherein it is preheated to a suitable flash temperature within the range about 500-850° F. The furnace 11 may be of construction conventionally employed for this purpose. The preheated fraction then passes through conduit 12 to tar separator 13 which may be a baffled tower of conventional construction. If desired, steam may be introduced into separator 13 through conduit 150 to assist in the vaporization of the lighter constituents of that charge. A vaporized fraction is withdrawn from the top of separator 13 and passed into the upper

section of a vertical converter 14 through conduit 15. A liquid fraction bearing high boiling oily and asphaltic constituents passes from the bottom of tower 13 through conduit 16 and is pumped by pump 17 through conduit 18 and exchanger 19 and cooler 151 into a deasphalting vessel 20. The deasphalting vessel is an elongated, vertical vessel which may be preferably of rectangular cross-sectional shape but which may be of other shape if desired. A solid inlet conduit 21 connects into the top of the vessel 20 and a drain duct 22 connects into the bottom of said vessel. A plurality of spaced heat transfer tubes 23 extend horizontally across the upper section of vessel 20 between an inlet header box 24 and an outlet header box 25. Cooling water under pressure may be pumped from a steam drum 26 by pump 27 into the inlet header box 24 via pipe 29. Hot water and steam may be returned to steam drum 26 via pipe 30. If desired, a heat exchange fluid other than steam may be employed. For example, a fused inorganic salt or low melting point fused metallic alloy may be circulated through tubes 23 and a suitable external cooler. Inverted troughs 31 are positioned across the vessel 20 below tubes 23 and pipes 32, closed on one end and perforated along their underside, extend along under troughs 31 and communicate with liquid charge conduit 18, outside of the vessel 20. Suitable baffles, not shown, may be positioned in the lower section of vessel 20 to insure uniform discharge of contact material from all sections of the vessel cross-section through outlet duct 22.

Below the outlet duct 22 is positioned a continuous perforated belt 35 which may be of screen construction for example. The belt passes over pulleys 36 and 37, the latter pulley being driven by means of motor 38. The continuous belt is encased in a gas tight chamber 39, and a receiving chamber 40 is provided adjacent the discharge end of the belt to receive discharged contact material. A drain pan 41 is positioned under the belt 35 near its charging end to receive liquid drainings. Suitable spray devices or wash solvent distributors 42 and 43 are provided over the belt 35 along a latter portion of its path of travel to distribute washing solvent onto the contact material carried on the belt 35. Drain pans 44 and 45 are positioned below the portion of the belt which is under the distributors 42 and 43, respectively. Liquid drainings containing the unsorbed asphaltic constituents of the feed stock are drained from pan 41 through conduit 47 into the receiver 48 from which it is discharged through conduit 49, pump 50 and conduit 51. If desired, a portion of the drainings from receiver 48 may be recycled to the deasphalting chamber via conduit 52 from which they enter the chamber 20 through perforated pipes 53, closed on the ends thereof within the vessel. Fins 54 are provided along pipes 53 to provide liquid distribution spaces thereunder. Liquid drainings from pan 45 pass via conduit 55 into receiver 56 from which it passes via conduit 33, pump 59 and conduit 60 into the first distributing device 42. Solvent for distributor 43 may enter from an outside source through conduit 61 to conduit 62 and then be pumped by pump 63 through conduit 64 to distributor 43. Alternatively solvent cycle oil may be withdrawn from a conventional conversion product fractionator 65 through conduit 66 from which it enters conduit 62. It will be noted that the arrangement described permits efficient use of the solvent in that fresh washing solvent is

sprayed onto the partially washed contact material just before the contact material is discharged from the perforated moving belt and the solvent employed for this final washing is recycled and used for the first stage of the contact material washing, being sprayed from distributor 42 onto the contact material on the belt 35 along an intermediate portion of its path of travel through chamber 39.

Spent washing solvent from pan 44 is drained via conduit 70 to receiver 71. Any entrained contact material fines may be removed from the bottom of receivers 71 and 56 through outlets 290 and 291 respectively. The spent washing solvent containing asphaltic material may then be passed from receiver 71 via conduit 67, pump 68 and conduit 69 to the upper section of tar separator 13 wherein it serves as a reflux or quenching fluid. At the same time the asphaltic constituents in the spent washing solvent are separated from the solvent in separator 13 so that the solvent may pass along with other vaporizable constituents to the conversion vessel 14. This type of operation is particularly attractive when a cycle gas oil cut from fractionator 65 or a virgin gas oil-cut is employed as the washing solvent. Since the spent solvent from receiver 71 may exist at a relatively low temperature it may be heated by exchange with tar separator bottoms in exchanger 19 to a suitable temperature for introduction into tower 13. Alternatively, all or part of the washings from receiver 71 may pass via conduits 69 and 72 to the inlet 10 to the heating furnace 11 so that it may be preheated and flashed in the tower 13 along with the charge stock. Where the solvents employed are other than gas oil or kerosene, it may be desirable to remove them from the system at 73 and treat them separately for removal of asphaltic constituents.

In order to permit uniform distribution of material from the deasphalting chamber 20 onto the moving belt 35, the discharge duct 22 from the deasphalting chamber may be of rectangular cross-sectional shape, extending in a direction perpendicular to the drawing substantially the width of belt 35. Suitable guard members, not shown, may be provided within chamber 39 to prevent contact material from falling off opposite sides of the belt 35. A slide valve 102 may be provided in duct 22 to permit control of the rate of material withdrawal from chamber 20. Any excess washing solvent which has failed to drain from the contact material by the time it is discharged from belt 35 may be purged from the contact material in receiving chamber 40 by the introduction of a suitable heated gas from conduit 74 into perforated distributor tubes 75 in chamber 40. The ends of tubes 75 within chamber 40 are closed. The purging gas should preferably be inert to the reaction in the conversion vessel. Exemplary of suitable purging gases are nitrogen, flue gas and steam.

A discharge conduit 76 is provided for withdrawal of contact material from receiving chamber 40 to seal chamber 77. At the bottom of chamber 77 there is provided a slide valve 78 which controls the flow of contact material from seal chamber 76 into conduit 79 which in turn directs the contact material into the upper section of conversion vessel 14. The conversion vessel 14 is a substantially vertical vessel of suitable cross-sectional shape provided with a solid inlet feed leg 130 extending upwardly from its top to a supply hopper 80 and with a solid discharge con-

duit 81 at its lower end. A partition 82 is supported across the upper section of vessel 14 to define a seal chamber 83. A conduit 84 depends centrally from partition 82 and terminates shortly therebelow. A cylindrical baffle curtain 85 is supported by rods 86 centrally below the conduit 84. A skirt 87 of substantially less cross-sectional area at its base than the curtain 85 extends downwardly from the lower end of conduit 83 and terminates just short of the lower end of curtain 85. A cylindrical baffle 88 having a conical shaped roof is supported by rods 131 directly below the lower end of conduit 83. The baffle 88 is of smaller diameter than skirt 87 so as to leave an annular passage 89 for contact material flow from conduit 83. A second annular passage 90 is provided for solid flow between skirt 87 and curtain 85. Into this latter passage contact material from conduit 79 is directed. The two separate streams of contact material from passages 89 and 90 are permitted to merge at the lower extremities of these passages and the merged streams pass into an inverted conical basin 91 supported by rods 92 and 92' within vessel 14 shortly below the lower end of curtain 85. The size and position of basin 91 with respect to curtain 85 is such as to prevent overflow of catalyst over the edges of the basin 91. Orifices 93 of predetermined size are provided in the bottom of basin 91 for discharge of mixed contact material therefrom. The above described arrangement for mixing the two separate inlet streams of particle-form contact material is only one of a number of arrangements which may be employed. It is contemplated that other suitable devices adapted for mixing of two inlet streams of contact material may be substituted for the arrangement described hereinabove. In the lower section of the vessel 14 there are provided two vertically spaced rows of spaced gas collecting troughs 95 and 96. Gas outlet conduits 97 and 98 are provided for troughs 95 and 96 respectively. The conduits 97 and 98 are manifolded into manifolds 103 and 104 respectively, which in turn are manifolded by means of conduits 105 and 106, respectively, into a single discharge conduit 107. Valves 108 and 109 are provided on conduits 105 and 106 respectively, to permit control of gas flow from each row of collecting troughs. It will be understood that other suitable arrangements for disengagement and withdrawal of gaseous products from the column of contact material in the convertor 14 may be substituted for that described hereinabove. Across the lower section of vessel 14, there are provided vertically spaced apart partitions 109 and 110. Short nipples 111 uniformly spaced apart depend from partition 109 and orifices 112 are positioned in partition 110 in staggered relationship to the nipples 111. It will be noted that the number of orifices is substantially less than the number of nipples. This arrangement which is fully described and claimed in United States application Serial Number 473,861, filed on January 28, 1943, now Patent No. 2,412,136, in which the present applicant is one of the applicants, permits the withdrawal of contact material uniformly from all sections of the horizontal cross-section of vessel 14 to the outlet conduit 81.

In order to permit better mixing and more uniform distribution of the contact material passing from basin 91, the orifices 93, which may preferably be adjustable, are set at such a size as to permit contact material discharge from basin 91 at the desired total throughput rate. The sur-

face level 142 of the contact material column is then maintained within a relatively narrow range of levels all below the basin 91 by adjustment in the rate of contact material withdrawal through conduit 81 by means of valve 99. The adjustment of valve 99 may be manual but an automatic rate adjusting system is preferable. A vertical rod 100 having fins 101 fastened along its length may be supported by suitable means (not shown) within that portion of the vessel in which it is desirable to maintain the column surface level. The rod 100 may be rotated by a motor 113 through shaft 114 and gears 145. As the surface level of the column changes along the rod 100, the power required to drive the electric motor 113 will vary. A suitable instrument 140 actuated by the change in power requirements for motor 113 will in turn actuate a motor 141 to drive valve 99 in such a manner as to compensate any change in the contact material column surface level at 142.

It will be noted that according to the method of this invention the gel-type contact material serves the dual function of a sorbent in the de-asphalting operation and as a catalyst for the conversion of the sorbed oily constituents in the conversion zone.

Along side of the convertor 14 there is provided a vertical regeneration vessel 115 having a solid inlet 116 at its upper end and a solid outlet 117 bearing valve 118 at its lower end. A suitable combustion supporting gas may be admitted to vessel 115 from manifold 119 through a plurality of vertically spaced gas inlet pipes 120. Gas may be withdrawn from the vessel 114 through a plurality of spaced pipes 121 which are vertically spaced from the inlet pipes in such a manner as to divide the vessel into a series of superposed burning stages each having separate spaced apart gas inlets and outlets. The outlet pipes 121 all connect into a common outlet duct 124. A plurality of cooling stages are provided alternating with the burning stages each cooling stage having a cooling fluid inlet 122 and outlet 123. Cooling tubes may be provided within each cooling stage communicating with the inlet 122 and outlet 123. A final cooling stage 195 provided with cooling fluid inlet 125 and outlet 126 is provided below the last burning stage. This type of regeneration vessel and the operation thereof is disclosed in United States Patent application Serial Number 447,432, filed June 17, 1942, now Patent No. 2,417,399, in which the present applicant is one of the applicants. It should be understood that it is considered to be within the scope of this invention to substitute other types of regenerator constructions which are adapted for the burning regeneration at controlled elevated temperatures of spent particle-form contact materials. A conveyor 127 is provided to transfer contact material from convertor 14 to regenerator 115 and a conveyor 128 is provided to transfer contact material from regenerator 115 to supply hopper 80. These conveyors may be of conventional construction adapted to transfer particle-form contact material at elevated temperatures without excessive attrition; as an example, continuous bucket elevators are satisfactory.

In operation of the above described system the heavy liquid fraction from separator 13 after being adjusted to a suitable inlet temperature by exchanger 19 and cooler 151 is sprayed by means of perforated tubes 32, which connect into inlet conduit 18, into the column of inorganic oxide

gel particles in the deasphalting chamber 20. Hot freshly regenerated gel-type contact material is supplied into the upper end of chamber 20 from supply hopper 80 via conduit 21 at a rate controlled by valve 152. The hot contact material is cooled to a suitable temperature for the deasphalting operation by means of cooling tubes 23. Hot water under pressure may be circulated through the tubes 23 by means of pump 27 to remove heat from the contact material. Low pressure steam generated may be withdrawn from the steam drum 26 through pipe 154. The temperature at which the deasphalting operation in chamber 20 is conducted may vary over a wide range, depending upon the properties of the liquid treated. The temperature should be high enough to give the oil sufficient fluidity to permit rapid sorption of the oily constituents but low enough to permit the contact material to function selectively. The maximum temperature maintained in the sorption zone is dependent on the viscosity of the stock being treated. The sorption of oily constituents becomes less selective as the viscosity decreases. The desirable sorption temperature has been found to vary from below room temperature to about 500° F. depending on the liquid fraction treated. The temperature of the liquid introduced through tubes 32 and the contact material passing into the sorption zone below the cooling tubes 23 should be controlled to provide the desired sorption temperature. The contact material should not be admitted to contact with the asphalt bearing liquid fraction at temperatures at which substantial thermal coking of the liquid fraction would take place. In general this means that the contact material should be cooled at least below about 750° F. before being permitted to contact the liquid charge.

The liquid charged from tubes 32 percolates downwardly through the column of downwardly moving contact material in the chamber 20. The residence time of the contact material within the chamber 20 may vary from about 1 to 10 hours depending upon the liquid fraction involved, the temperature and the ratio of the contact material to the liquid charge. In many operations it is desirable to control the residence time of the contact material in chamber 20 by means of valve 102 such as will permit substantial saturation of the contact material with sorbed oily constituents.

The ratio of contact material to liquid charge to the deasphalting chamber may vary from about 0.5 to 20 parts by weight of contact material per part of liquid asphalt bearing charge and preferably from about 2 to 6 parts of contact material per part of liquid charge.

The gel-type contact material bearing oily constituents sorbed in its pores and the liquid asphaltic material which remains substantially unsorbed is directed from chamber 20 onto the perforated moving belt 35. During that portion of the belt travel directly over the pan 41 most of the asphaltic liquid is drained from the contact material and withdrawn via conduit 47 to receiver 48. In some operations it may be necessary to recycle a portion of the recovered liquid from receiver 48 to chamber 20 in order to insure substantially complete separation of oily constituents from the asphaltic constituents in the liquid fraction. During that portion of the travel of belt 35 in which it moves over pans 44 and 45, a suitable washing solvent is sprayed or poured onto the contact material by means of devices

42 and 43 in order to wash away asphaltic material which adheres to the outer surface of the contact material particles. The amount of solvent employed in the washing step may vary from about 0.25 to 2.0 volumes of solvent per volume of contact material depending upon the particular operation and solvent involved and upon the viscosity of the unsorbed liquid. The washed contact material is then purged or blown in receiving chamber 40 by means of a suitable heated purge gas in order to remove from its outer surface any adhering liquid so as to thereby improve the flowability of the contact material particles. In some operations it is desirable to partially preheat the contact material at this point either by means of the hot purge gas or by means of indirect heat transfer with a suitable heating fluid. Alternatively, the contact material from washing chamber 39 may be partially preheated by passing the hot regenerated contact material charge to chamber 20, in indirect heat transfer relationship with the cooler washed contact material before the introduction of the regenerated contact material into the deasphalting chamber 20. It is also contemplated to be within the scope of this invention to charge the washed contact material directly into the reactor without an intermediate purging or heating step.

While the above described apparatus for conducting the deasphalting and the draining and washing operations represent a preferred form of this invention, nevertheless other suitable arrangements are contemplated as being within the broad scope of this invention. For example, in operations wherein the ratio of liquid to solid material charge to the deasphalting operation is high, a mixing vessel adapted to handle the solid material and liquid as a slurry may be employed as the deasphalting chamber and after the proper residence time in the sorption zone the slurry may be treated in a continuous rotary type filter for separation of asphaltic liquid from the contact material particles and for washing of the particles. Moreover, in some operations, particularly those wherein the liquid involved is of relatively low viscosity, the washing step may be eliminated and the asphaltic liquid adhering to the particles may be removed by purging and/or draining.

The washed and purged contact material bearing sorbed oily constituents then passes from chamber 40 downwardly through leg 76 into seal chamber 77 wherein an inert gaseous pressure is maintained slightly above that in section 160 of convertor 14 by means of gas introduction through pipe 161 at a rate controlled by automatic diaphragm operated valve 162. Contact material passes from chamber 77 at a rate controlled by slide valve 78 into conduit 79 by which it is directed into the mixing device in the upper section of convertor 14. Hot regenerated contact material from hopper 80 passes downwardly through the gravity feed leg 130 into the seal chamber 83 wherein an inert gaseous pressure is maintained slightly above the pressure in space 160 by means of gas introduced through pipe 165 at a rate controlled by diaphragm valve 166. The gas introduced to both seal chambers 77 and 83 may be steam, flue gas, nitrogen, etc. The hot regenerated contact material passes downwardly from seal chamber 83 via conduit 84 into the mixing device. The stream 89 of hot regenerated contact material mixes with the stream 90 of cooler contact material bearing sorbed oily constituents so as to

heat the latter stream to a temperature suitable for conversion of the oily constituents to lower boiling gaseous hydrocarbon products. The mixed contact material then passes as a shower from basin 91 through orifices 93 onto the surface 142 of the column of contact material maintained therebelow and then passes downwardly within said column so that the oily constituents are catalytically converted to lower boiling gaseous products. It should be understood that the word "gaseous" as employed herein in describing and in claiming this invention is intended in a broad sense as meaning material existing in the gaseous phase under the particular conditions of temperature and pressure involved regardless of the normal phase of such material under atmospheric conditions. The gaseous products are disengaged from the column of contact material in the lower section of the conversion zone by means of inverted collecting troughs 95 and 96 from which it is withdrawn through conduits 97 and 98 respectively. As pointed out hereinabove the vaporized constituents of the original petroleum charge may be introduced into the upper section of convertor 14 through conduit 15. The vaporized material then passes downwardly through the column of contact material in the conversion zone so as to become converted to lower boiling gaseous hydrocarbon products. These latter products are withdrawn through pipes 97 and 98 in admixture with the gaseous products from the liquid oily constituents which were recovered in the deasphalting chamber. In some operations it may be desirable to convert the vaporized portion of the petroleum charge obtained from tar separator 13 in a separate conversion system in which case it is passed to the separate system from conduit 15 via conduit 167 instead of being introduced into convertor 14. The mixed gaseous products from convertor 14 are directed through conduit 107 into a suitable fractionator 65. Gasoline and lighter products are withdrawn from the top of fractionator 65 via conduit 168, a portion of this stream being condensed in cooler 169 and refluxed via conduit 170 and a portion being withdrawn via conduit 171 for further fractionation. A light cycle stock boiling within the range about 450° F. to 850° F. is withdrawn from fractionator 65 via conduit 66. A portion of this cycle stock may, if desired, be employed as the washing solvent and the remainder of this cycle stock is withdrawn through conduit 172 either to be recycled to furnace 11 or to be used for purposes outside of the system. A heavy cycle stock is withdrawn as a product from the bottom of the fractionator 65 via conduit 173. In many operations it has been found desirable to recycle this heavy cycle stock either to furnace 11 or separator 13 in order that it may be ultimately converted to lower boiling products.

The operating conditions within the convertor 14 will vary depending upon the activity of the catalyst employed, the particular petroleum charge involved, the reaction involved and the products desired. In general it has been found desirable to maintain the pressures within a range varying from subatmospheric to about 200 pounds per square inch. Pressures of the order of 5 to 50 pounds per square inch gauge are preferred. The temperature for the conversion for cracking operations may vary from about 800° F. to 1100° F., temperatures of the order of 850° to 1000° F. being preferred where gasoline is the desired product. Where non-

condensable gases are the principal desired product somewhat higher temperatures may be employed. The ratio of contact material to hydrocarbon throughput may vary from about 1.0 to 5 40 parts by weight of contact material per part of hydrocarbon charge. The ratio of fresh hot regenerated contact material introduced via conduit 84 to that bearing sorbed oily constituents and introduced via conduit 79 should be so controlled that the resulting temperature of the mixture is suitable for accomplishing the desired hydrocarbon conversion. The exact ratio used may be varied somewhat by control of the temperature of the hot regenerated contact material supplied to hopper 80 and by control of the amount of preheat given the washed contact material from chamber 39. It has been found preferable to employ about 2 to 10 parts by weight of fresh hot regenerated contact material per part of the contact material bearing the oily constituents from the deasphalting operation.

The amount of hot contact material employed may be substantially reduced in many operations 25 by directing the vaporized hydrocarbons from tar separator 13 through conduits 15 and 9 into heater 8 wherein it is heated to a temperature above the desired reaction temperature and then passed via conduits 7 and 15 to the converter. If 30 desired a lighter and more thermally stable hydrocarbon feed such as light gas oil, naphthas or even normally gaseous hydrocarbons may be introduced at 6 into the heater 8 and then introduced into the converter to supply part of the 35 heat requirements therein.

The spent contact material bearing carbonaceous contaminant deposited is purged substantially free of vaporizable products by means of a suitable purge gas such as steam or flue gas introduced through conduit 183, and the purged contact material is withdrawn from the converter through conduit 81. The rate of contact material throughput is controlled by orifices 93 in basin 91 and the rate of withdrawal via conduit 40 81 is automatically controlled by valve 99 to maintain the level column surface level 142 within a relatively narrow constant range. The spent contact material is conveyed by conveyor 127 to the top of regenerator 115. The contact material passes as a substantially compact column downwardly through regenerator 115 while being subjected to alternating stages of burning and cooling as described hereinabove. In general during the regeneration the contact material should be maintained at a level suitable for rapid contaminant combustion but below a heat damaging level. The heat damaging level is that level at which the contact material suffers a permanent loss in its catalytic and/or sorptive efficiency and may vary 45 from about 1150° F. to 1450° F. depending upon the particular inorganic oxide gel-type catalyst involved. The temperature of the regenerated contact material may be adjusted to the level desired in hopper 80 by means of the cooling section provided below the lowermost burning stage.

Since the system described hereinabove depends upon gravity flow of contact material from the level of hopper 80, which is generally at a 50 relatively low pressure, to the mixing device in space 160 of convertor 14 wherein the gaseous pressure is higher, it is necessary to operate the washing chamber 39 under a pressure intermediate that in hopper 80 and that in section 160 of the convertor. The pressure mentioned in

chamber 39 should be sufficiently high when combined with the head of contact material provided in conduit 76 to force contact material flow into seal chamber 17. The required pressure is maintained in chamber 39 by means of a suitable inert gas introduced thereinto through conduit 180 at a rate controlled by diaphragm valve 181 and differential pressure controller 182. It is also important in the system described that the mixed solid-liquid head in deasphalting chamber 20 be sufficient to force the flow into chamber 39. While this gravity flow type of system is preferred because it permits movement of the catalyst particles with the least amount of attrition thereof, it is nevertheless considered within the scope of this invention to substitute forced feed devices between the several vessels to accomplish transfer of solid material therebetween without necessary resort to gravity flow.

The system described hereinabove is adapted particularly for handling original petroleum charge stocks of relatively broad boiling range which charge stocks contain vaporizable fractions as well as heavy liquid oil and asphalt fractions. The method and apparatus of this invention is capable of handling not only such petroleum stocks of broad boiling range but also heavier residual stocks high in asphalt content and essentially stripped of vaporizable gas oil. In Figure 2 there is shown an arrangement particularly adapted for handling such heavier stocks. Figure 2 also shows a modified arrangement for washing the contact material from the deasphalting zone and for introducing it into the conversion zone. Like elements of the systems in Figures 1 and 2 bear like numerals and the description thereof given under Figure 1 may be applied to same elements in Figure 2. In the system shown in Figure 2, high boiling residuum charge is introduced directly into the deasphalting chamber 20 via conduit 190 after being subjected to preliminary heating in exchanger 191 by means of the steam produced in cooling the hot regenerated catalyst supply for chamber 20 to a suitable temperature for the deasphalting operation. The deasphalting chamber employed may, if desired, be substantially the same as that employed for the processing of tar separator bottoms. The chamber 20, shown in Figure 2, is substantially the same as that shown in Figure 1 except for a modification in the solid and liquid mixing section. In the apparatus of Figure 2 a partition 193 is provided across the chamber 20 between the solid cooling and the sorption zones. Conduits 194 depend from the partition 193 for flow of cooled contact material to the sorption zone. The conduits provide a solid excluded space 195 into which liquid inlet headers 196 bearing spray nozzles 197 extend. Thus the liquid charge may be sprayed onto the surface of the contact material column in the sorption zone. A star type discharge valve 203 which may extend a substantial distance horizontally in a direction perpendicular to the face of the drawing is provided on the discharge duct 22 from chamber 20.

The contact material and unsorbed asphaltic liquid are directed by dust 22 onto the moving foraminous belt 198 in drain chamber 199. The chamber 199 differs from chamber 39 of Figure 1 in that it is devoted entirely to the draining operation wherein chamber 39 is devoted to both the draining and washing operation. Drained liquid bearing asphalt constituents passes through the foraminous screen into pan 41 from which it is withdrawn to receiver 48 via pipe 47. This

liquid may either be withdrawn from the system or in part recycled from receiver 48 to chamber 20 as described in connection with Figure 1.

The contact material from which unsorbed asphaltic liquid has been drained falls off the discharge end of belt 198 into a column of washing solvent maintained in a baffled washing chamber 200. The contact material falls through the column of liquid in chamber 200 in a zig zag path enforced by baffles 201 and passes from the bottom of chamber 200 into the boot section of a bucket type elevator 203 which communicates with chamber 200. The washed contact material is picked up by buckets 204 which may have perforated bottoms so that the wash solvent may be drained from the contact material as it is transferred to the top of the elevator. The elevator may be inclined rather than vertical or the buckets may be adequately shaped to prevent liquid draining from one bucket from falling into a bucket therebelow. The contact material is discharged from elevator 203 via chute 205 into the hopper 206 wherein it may be subjected to a partial preheat by means of indirect heat transfer with a suitable heat exchange fluid passed through tubes 207. If desired, a suitable heating and purging gas may be introduced into hopper 206 through manifold 208 and perforated tubes 209. In a preferred form of the operation hot cycle oil may be withdrawn from product fractionator 65 via conduit 66 and pumped by pump 210 through conduit 211 into the inlet header box 212 supplying tubes 207 in hopper 206. The cycle oil thus serves to heat the contact material to a temperature of the order of about 400° F.-700° F. and is in turn cooled to a suitable temperature for its use as a washing solvent. The cooled cycle oil passes from outlet header box 213 into conduit 214 by which it is directed into the boot section of the elevator 203 at the desired level. The cycle oil then passes from the boot section of the elevator 203 upwardly through the washing chamber 200 from which it is withdrawn through conduit 216 to receiver 217. Any entrained undersized contact material is separated from the used washed oil in receiver 217 and withdrawn through outlet 218. The used washing oil is pumped by pump 219 via conduit 230 through exchangers 220 and 221 into a separate fractionating tower 222 wherein the cycle oil is recovered from the asphaltic material. The cycle oil may be withdrawn from the top of fractionator 222 via conduit 224 and condensed in exchanger 220. A portion of the condensate is refluxed to tower 222 via conduits 227 and 228 and the remainder may be withdrawn from the system via conduits 227 and 229 or returned to the system via conduits 227 and 66. Heavy cycle stock from fractionator 65 may be passed via pipe 173 through exchanger 221 to supply heat to the wash cycle oil. Asphalt may be removed from fractionator 222 via conduit 231.

If desired, instead of employing cycle oil from fractionator 65 a suitable washing solvent such as a naphtha fraction may be introduced directly into the boot section of elevator 203 via conduit 235 instead of cycle oil from fractionator 65. In this case the used washing solvent may be separated from asphaltic constituents in the same manner described for the cycle oil, and a substitute heat exchange fluid may replace the cycle oil in the tubes 207 in hopper 206. In an alternative operation the used washing solvent from receiver 217 may be passed through tubes 23 in the deasphalting chamber 20 as the cool-

ing fluid in place of hot water. The washing oil which has become heated by the hot catalyst from conduit 21 may then be introduced into fractionator 222. In this operation the residuum liquid charge may be introduced cold into the deasphalting chamber and the inlet contact material may be adjusted to a temperature sufficient to heat the oil upon mixing therewith to a suitable temperature for the deasphalting operation. In still another alternative operation the spent washing solvent from receiver 217 may be withdrawn via conduits 23° and 350 to be incorporated as cutting stock in refinery fuel blends thereby eliminating the fractionator 222.

The washed and partially heated contact material from hopper 206, still bearing sorbed oily constituents may be passed downwardly through a gravity feed leg 236 wherein it flows as a substantially compact column into the seal chamber 237. A gaseous pressure slightly above that in zone 160 of converter 14 is maintained in seal chamber 237 by introduction thereinto of a suitable inert seal gas via conduit 239 at a suitable rate controlled by diaphragm valve 240 and differential pressure control instrument 241. The pressure maintained in seal zone 237 and in seal zone 83, into which hot regenerated catalyst is supplied should be of the order of about one-quarter to one pound per square inch above that in zone 160 of converter 14. The contact material from seal zone 237 passes therefrom via conduit 244 at a suitable rate controlled by slide valve 245 and is directed into the upper section of the curtained zone defined by cylindrical curtain 246. The hot contact material stream from conduit 84 is caused to mix with the cooler contact material from conduit 244 by means of the baffle members 87 and 88, which are similar to the same members in Figure 1, working together with the cylindrical curtain 246 which directs the mixed contact material onto a conical baffle 248 supported by rods 249 at a level substantially below the lower extremity of members 87 and 88. A basin 250 which is of less diameter than vessel 14 but of greater diameter than the base of conical baffle 248 is supported by rods 251 below the baffle 248 so as to receive the contact material flow therefrom. The relative height of the sides of the basin 250 and the lower extremity of curtain 246 are fixed in such relationship as to prevent contact material from overflowing the basin 250. Contact material passes from basin 250 through a plurality of uniformly spaced conduits 253 onto the surface 254 of the contact material column in the vessel 14. The number and size of conduits 253 are such that the conduits 253 provide a solid flow capacity in excess of the maximum anticipated rate of flow. The above described arrangement differs from the mixing device shown in the converter 14 of Figure 1 in that in the arrangement of Figure 2, the total rate of contact material flow through the converter is controlled only by means of valve 255 on the reactor bottom outlet 81 so that continuity of solid column is maintained from the valve 255 up through the solid mixing device, while in the arrangement of Figure 1, the rate of solid flow is controlled by the orifices 93 in basin 91 and the contact material is caused to shower through a short vertical section of converter 14 before reaching the column surface. In still another form of this invention the mixing device and basin shown between partition 82 and the contact material column surface may be eliminated and the mixing of the two contact material streams may be effected at the surface or in the upper portion

of the column itself. For example, a plurality of spaced pipes may extend down from partition 82 in the apparatus of Figure 2 to the column surface to deliver hot contact material onto the column. 5 Also a plurality branch conduits may extend down from the end of the conduit 244 to the surface of the column for delivery of the cooler contact material onto the column surface at a plurality of points distributed uniformly across the column area. If desired these latter branch pipes may extend a short distance below the column surface. Also if desired the contact material from conduit 244 may be showered down through an upper vertical portion of the vessel onto the surface of the column while the hot contact material is delivered directly onto the column as described.

10 It will be noted that in the arrangement shown in Figure 2, the provision of gravity feed leg 236 eliminates the necessity for operating the draining and washing chambers 199 and 200 respectively, under controlled pressures intermediate those in hopper 80 and in the convertor 14.

The arrangements described above all involve the passage of the mixed contact material through 15 a confined conversion zone as a substantially compact column. This is the preferred form of this invention because it permits more accurate control of the catalyst residence time in the conversion zone, avoids channeling difficulties, limits to a minimum the attrition of the catalyst, which 20 must of necessity be made up of particles which are 30 mesh in size or larger and offers certain other advantages. Nevertheless, in the broader aspects of this invention it is contemplated to be 25 within the scope of this invention that the catalyst particles may be passed through the conversion or regeneration zones or both in suspension in a gas stream or handled as a fluidized mass. Also 30 in another less preferred operation the oil bearing contact material may be mixed batchwise in a single vessel with hot regenerated contact material and the mixture may be maintained substantially stationary in the vessel for the desired 35 length of time, while the gaseous products are 40 withdrawn from the vessel as formed.

45 As will be understood from the above discussion of the invention, a portion of the regenerated catalyst is further cooled and supplied to the deasphalting zone while the remaining portion 50 is transferred hot to the upper section of the conversion zone to mix with and heat the oil bearing catalyst from the deasphalting apparatus. While it is the preferred form of this invention to mix fresh hot regenerated catalyst with 55 the oil bearing catalyst from the deasphalting zone, nevertheless in the broader aspects of this invention it is contemplated that the hot catalyst which is mixed with the oil bearing catalyst from the deasphalting operation may be hot 60 partially regenerated catalyst or even used catalyst from the converter discharge which has been heated and recycled to the seal zone 83. Such a modified arrangement is shown in Figure 3. In the arrangement shown in Figure 3 the asphalt bearing liquid charge is introduced via conduit 300 into deasphalting chamber 301 wherein it is contacted with inorganic oxide gel-type contact material particles which are introduced at a suitable 65 temperature through duct 302. The contact material and unsorbed asphalt containing liquid then pass into chamber 303 wherein they are separated. The contact material is then washed in chamber 304 with a suitable solvent introduced at 305 and withdrawn at 306. The washed contact 70 material is then transferred by conveyor 307

to hopper 308 from which it flows through a gravity feed leg 309 to seal chamber 310. The contact material passes via conduit 311 from seal chamber 310 to mixing chamber 312 wherein it is mixed with hot, at least partially spent contact material entering chamber 312 via conduit 313 from seal chamber 314. The mixed contact material passes at a suitable conversion temperature into the top of convertor 315 via conduit 316. Gaseous conversion products are withdrawn from the convertor via conduit 317 and spent contact material bearing a carbonaceous contaminant, after being purged by a suitable gas introduced into chamber 315 at 318, is withdrawn from the bottom of convertor 315 via conduit 319 at a rate controlled by valve 320. A portion of the spent contact material is transferred via conveyor 321 to chute 322, feeding the reconditioner 323. In the reconditioner the contact material is heated to a suitable temperature for heating the oily constituent bearing contact material from hopper 308 to the desired conversion temperature. The contact material heating in vessel 323 may be accomplished either by direct or indirect heat transfer with a suitable heated heat exchange fluid introduced at 324 and withdrawn at 325. On the other hand a mixture of gaseous fuel and air may be introduced at 324 to burn and thereby heat the contact material. Preferably, however, a combustion supporting gas may be introduced at 324 at a rate such as will promote the burning of just a sufficient portion of the contaminant deposited on the contact material to heat the contact material to the required temperature. By properly controlling the gas introduced at 324, the contact material may be heated to the desired temperature level without overheating it to a heat damaging level and without the need for any cooling tubes within or after the chamber 323. In this operation the hot contact material passing from chamber 323 through gravity feed leg 325 to seal chamber 314 is partially regenerated catalyst. The remainder of the spent contact material from convertor 315 is transferred via conveyor 321 to chute 327, feeding to the regenerator 328 wherein it is substantially completely regenerated by means of air or oxygen, etc., introduced at 329 and withdrawn at 330. A suitable cooling fluid may be introduced through conduit 331 to suitable heat transfer tubes (not shown) within the regenerator in order to control the contact material temperature below a heat damaging level during the contaminant burning. The cooling fluid may be withdrawn from the heat transfer tubes via conduit 332. The regenerated contact material passes from regenerator 328 to cooler 333 wherein it is cooled by means of a suitable cooling fluid introduced at 334 and withdrawn at 335. The cooled contact material passes from cooler 333 via conduit 336 and is transferred by conveyor 337 to conduit 302 feeding the deasphalting chamber 301. An inert gas, such as steam, may be supplied to seal chambers 310 and 314 through conduit 338 at a rate controlled by valve 339 sufficient to maintain an inert gaseous pressure in both seal chambers above the gaseous pressure in catalyst mixing chamber 312. If desired, a vaporized hydrocarbon charge may also be introduced into the convertor through conduit 339. The relative amounts of spent catalyst passing from conveyor 321 to regenerator 328 and to reconditioner 323 may be controlled by means of valves 340 and 341 on chutes 327 and 322 respectively. Alternatively two separate conveyors may be used at this point in the system.

By way of example of this invention, a mid continent crude petroleum residuum having the following properties may be deasphalting in a suitable deasphalting chamber in the manner described:

A. P. I. gravity	19.4
Pour point	45° F.
Saybolt Universal viscosity at 210° F.	167 seconds
10 Conradsen carbon residue	9.4% by weight
Sulfur	1.5% by weight
Cleveland open cup flash	435° F.
Cleveland open cup fire	505° F.
15 Using a silica alumina spheroidal gel catalyst of about 40 pounds per cubic foot unpacked density and average particle size of 0.129 inch (4-10 mesh size Tyler), prepared by the method described in United States Patent 2,384,946, issued September 18, 1945 to Milton Marisic, in a ratio of about 290 parts of sorbent per 100 parts of residuum charge by weight and maintaining atmospheric pressure and a temperature of about 300° F. and residence time of about two hours in the continuous type deasphalting chamber, and recycling the unsorbed liquid until substantially all the oily constituents have been removed, oily constituents amounting to about 85% of the charge may be separated from the asphaltic constituents contained in the above residuum charge. The catalyst bearing the sorbed oily constituents is washed with about one half its weight of a light cycle oil, the residence time of the catalyst in the washing operation being limited to about 3 minutes. The catalyst before charging to the reactor contained about 29% of its weight of sorbed oily constituents having the following properties: A. P. I. gravity—23.9, Saybolt Universal viscosity at 210° F. 83.3, kinematic viscosity at 100° F.—210, Conradsen Carbon — 1.75% weight. The catalyst bearing sorbed oily constituents and existing at about 210° F. was mixed together with hot regenerated catalyst of similar type existing at about 1090° F. by flowing the two catalyst streams into a closed vessel and mixing the catalyst in the vessel. The weight ratio of hot to cold catalyst mixed exclusive of oil, was about 1.9 to one. The vaporous reaction products were withdrawn from the top of the closed vessel as fast as formed and the mixed catalyst was maintained in the vessel for about 10 minutes before withdrawing it. The estimated reaction temperature was about 960° F. and the pressure was substantially atmospheric. The following conversion yields were obtained corrected to a no loss basis:	
Gasoline 410° F. E. P. of low vapor pressure	26% by weight of sorbed oily constituents
60 Cycle Oil	45.4
Gas (Including C's and C's) (Dumas Gravity 1.169)	17.6% by weight of sorbed oily constituents
65 Coke on Catalyst	11.0% by weight of sorbed oily constituents
70 The coke deposited on the catalyst was only 1.1% by weight of the catalyst and was readily removed by burning at temperatures within the range about 800° F.-1100° F. It will be noted that in the above yield data the gasoline had not been stabilized and the gas contained a considerable	

amount of gasoline constituents. The above substantial gasoline yields were obtained even though in the batch type operation described in this example, the vapors were withdrawn substantially instantaneously as formed so that the time of contact of vapors with catalyst was extremely short. In the continuous type operation described herein wherein vapors formed must pass downwardly through a substantial length of catalyst column before being withdrawn, substantially higher gasoline yields without substantial increase in coke may be expected for operating conditions similar to those in the above example.

It will be apparent from the above that by the method of this invention very heavy petroleum charge stocks may be handled without incurring coke deposits on the catalyst substantially heavier than those heretofore incurred in handling much lighter, clean gas oil charge stocks.

It should be understood that the specific details of apparatus construction and of operating conditions and of conversion applications of this invention given hereinabove are illustrative and are not intended as limiting the scope of this invention except as it may be limited by the following claims.

I claim:

1. A process for catalytic conversion of the oily constituents in asphalt bearing high boiling hydrocarbon fractions to lower boiling products at controlled elevated temperatures in the presence of a particle-form catalyst which comprises: contacting the asphalt bearing fraction with a particle-form catalyst existing at a temperature below about 750° F. which is substantially below the temperature at which said fraction undergoes conversion to lower boiling products and having a structure in which the total macropore volume is less than about 30 percent of the total pore volume and the minimum average particle diameter is greater than about 60 mesh while controlling the temperature suitable for sorption of oily constituents by said catalyst, separating the unsorbed asphaltic constituents from the catalyst and passing the catalyst bearing sorbed oily constituents in admixture with a sufficient quantity of hot freshly regenerated catalyst of the same type to heat it to a suitable temperature for conversion of said oily constituents at least in part to lower boiling gaseous hydrocarbon product downwardly through a confined conversion zone as a substantially compact column to effect conversion of said oily constituents to gaseous hydrocarbon product, said hot catalyst existing initially at a temperature substantially above said suitable conversion temperature, withdrawing said gaseous product from said conversion zone, separately withdrawing used catalyst bearing carbonaceous contaminant deposited from said conversion zone, passing said used catalyst through a separate burning zone while contacting it therein at controlled elevated temperatures with a combustion supporting gas to burn said deposits, and mixing the regenerated catalyst while hot with said catalyst bearing oily constituents as aforesaid.

2. A process for conversion of a liquid hydrocarbon charge to a lower boiling product which comprises, contacting the liquid hydrocarbon charge with a particle form solid adsorbent catalyst existing at a temperature below about 750° F., which is below that at which said charge will vaporize and substantially below that at which said charge will undergo conversion to a lower boiling product, to effect sorption of the charge onto said catalyst, mixing said catalyst

bearing the liquid charge with sufficient hot catalyst material of similar type existing at a temperature substantially above the conversion temperature to heat the liquid bearing catalyst to a temperature suitable for converting said charge at least in part to lower boiling vaporized products, passing the mixture through a conversion zone to complete said conversion, separating the vaporized products from the spent catalyst, passing the spent catalyst through a regeneration zone while contacting it with an oxygen containing gas therein to burn off contaminants deposited on the catalyst, cooling a portion of the regenerated catalyst and reusing for sorption of liquid charge and utilizing the remainder of the regenerated catalyst as the hot catalyst for admixture with the liquid bearing catalyst.

3. A process for conversion of a high boiling liquid hydrocarbon charge to a lower boiling product which comprises, contacting the liquid hydrocarbon charge with a particle-form solid sorbent contact material existing at a temperature below about 750° F. which is substantially below the temperature for said conversion so as to effect sorption of said liquid into the pores of said sorbent, mixing said sorbent bearing the liquid charge with sufficient hot sorbent contact material of similar type existing at a temperature substantially above the desired conversion temperature to heat the liquid bearing sorbent to a temperature suitable for converting said charge at least in part to lower boiling vaporized products, passing the mixture through a conversion zone to complete said conversion and separating the vaporized lower boiling products from the sorbent.

4. A process for the conversion of oily constituents present in asphalt bearing high boiling liquid hydrocarbon fractions which comprises: contacting the asphalt bearing fraction with a porous particle form catalyst material of substantial particle size as distinguished from powdered contact material and having its pore volume devoted mostly to micropores and less than 30 percent of its pore volume devoted to pores having radii greater than about 100 Angstrom units to effect sorption of the oily constituents of said fraction in the pores of said catalyst material particles, said catalyst material existing at a temperature below about 750° F. which is below the conversion temperature, effecting a substantial separation of unsorbed liquid from the catalyst material particles bearing sorbed oily constituents and mixing the separated catalyst material bearing said oily constituent with sufficient hot catalyst material of similar type existing substantially above the desired conversion temperature to heat the oil bearing catalyst material to a temperature suitable for the desired conversion of said oily constituents.
